H. INGRAHAM.
Base-Burning Cooking-Stoves.

No. 140,138.

Patented June 24, 1873.

UNITED STATES PATENT OFFICE.

HANFORD INGRAHAM, OF NAPLES, NEW YORK.

IMPROVEMENT IN BASE-BURNING COOKING-STOVES.

Specification forming part of Letters Patent No. 140,138, dated June 24, 1873; application filed April 5, 1873.

To all whom it may concern:

Be it known that I, HANFORD INGRAHAM, of Naples, in the county of Ontario and State of New York, have invented certain Improvements in Coal Cook-Stove, of which the following is a specification:

Figure 1 is a side view of the stove. Fig. 2 is a plan view of the top of the stove, embracing the arrangement of flues and boiler-holes, magazine and magazine-case. Fig. 3 is a perspective view of the extra movable flues.

The nature of my invention consists in an improvement on a self-feeding coal cooking-stove. The body of the stove is so constructed as to admit in its center a fire-pot, A, below and a magazine, B, above the top of the stove C. A space is left in the shell H of the stove, which projects out from the top of the fire-pot and the case E of the magazine, sufficient to admit of the bottoms of the cooking-utensils, and the extra movable flues D D D which are placed between them. The magazine is surrounded by a case, E, of a concave and convex shape, to admit of the required number of boiler-holes F F F, which are placed in a circular form round the magazine, and to form a suitable space for the draft. The concave part of the case of the magazine comes in contact with the magazine, which brings the holes for the cooking-utensils nearer the magazine and further over the fire-pot. The convex part leaves a space between the boiler-holes for the draft of the stove, which passes up between the magazine and the case. The draft is changed and brought in contact with the bot-

toms of the cooking-utensils by means of a kind of extra movable flue, D D D, with sides and bottom, and open at each end, which is placed against the under side of the top of the stove, and may be replaced by another when injured by the action of the heat, and is supported by means of an extra plate or brace below, which rests on the under plate H of the shell of the stove, by which means the direct draft upward is changed and brought in contact with the bottoms of the cooking-utensils, thence into the front end and through the extra flue, thence up and through the concave part of the magazine to and around the oven I, thence to the pipe on the top of the oven. The grate to the coal-pot is operated by means of a lever, which is inserted in an opening at the top of the hearth. A griddle, M, is placed in the bottom of the oven I, and in the top of the magazine B, which may be removed for the purpose of supplying the magazine with coal.

I claim—

1. The extra movable flues D D D or their equivalent, for the purpose and in the manner substantially as and for the purpose hereinbefore set forth.
2. The combination of the extra movable flues D D D, the boiler-holes F F F, the magazine B, the magazine-case E, the oven I, substantially as and for the purpose hereinbefore set forth.

HANFORD INGRAHAM.
